UNITED STATES PATENT OFFICE.

SAMUEL FRIEDMAN, OF BROOKLYN, NEW YORK.

FUR BRUSHING, STRAIGHTENING, AND BEATING MACHINE.

Application filed September 15, 1925. Serial No. 56,541.

My invention relates to a machine for treating furs whereby to subject the same to treatment that will cause the hair to be straightened out and by a preliminary treatment give the final beater to which the fur eventually passes, increased effectiveness in raising the hair on the skin.

The general object of my invention is to provide a machine efficient in carrying out its functions as outlined and be effective for proper raising of the hair.

The nature of my invention, the distinguishing features and advantages will clearly appear as the description proceeds.

Reference is to be had to the accompanying drawings forming a part of this specification, it being understood that the drawings are merely illustrative of one example of the invention.

Figure 1 is a transverse vertical section of a machine embodying my invention as indicated by the line 1—1, Figure 2;

Figure 2 is a rear elevation of the machine.

In the illustrated example of my invention, the numeral 10 indicates a revolving brush to which the fur A is fed by means of a pair of feed rollers 11. From the feed brush 10 the fur A runs past a beater 12 and thence between a concave 13 and pressing roller 14 to the final beater 15. The brush 10 is known in its brushing function and also the final beater 15 and need not be described in detail. Arrows in Figure 1 indicate the path of a fur through the machine and the curved arrows indicate the direction of revolution of the respective rollers and beaters. It will be apparent from Figure 1 that the fur passing through the feed roller 11 is subjected to the action of the brush 10 which partially raises the fur. In the passage of the fur from the brush to the concave 13 and roller 14, the fur is subjected to the action of the beater 12 for further raising the fur. The action of the roller 14 and concave 13 is to loosen the hair and raise it. The fur or hair has a very pronounced tendency to rise following the subjection of the skin to heat. Therefore, when the fur passes from the concave 13, the fur of the skin immediately rises. The complete raising of the fur being then accomplished by the beater 15 having resilient blades as in beaters of this kind employed in fur brushing and beating machines.

The provision of the concave 13 and heated roller 14 is found to be particularly effective for raising and straightening the hair on the skin and its location following the preliminary hair brushing by the brush 10 and the action of the beater 12 assists in raising the hair, the roller and heater concave then serving to effectively straighten the hair. The heat of the concave 13 is particularly effective because the hair side of the skin is brought into contact with the concave and at the same time the fur is given a curved bend by reason of the proximity of the roller 14 to the concave 13.

Various means may be employed for driving the different revolving brushes, rollers, and beaters. In the illustrated example the motor 50 is conventionally shown on the shaft 16 of which motor is a pulley 17 over which a belt 18 runs to and about a pulley 19 on the shaft 20 of a fan 21. The inlet of the fan is connected with a suction trunk 22 which leads from a housing 23 surrounding the brush 10 so that the dust raised by the action of brush 10 is drawn to the fan 21, the outlet 24 of which leads to any desired point. A belt 25 runs over a second pulley 26 on motor shaft 16 and about a pulley 27 on the shaft 28 of brush 10 whereby to drive said brush. A belt 29 runs from the pulley 30 on shaft 10 to a pulley 31 on a counter-shaft 32 and said counter-shaft has a second pulley 33 over which a belt 34 runs, said belt extending also about a pulley 35 on the shaft 36 of beater 12. Running over the pulley on shaft 36 is a belt 37 which runs also over a pulley on the shaft of one of the feed rollers 11. Said shafts of the feed rollers 11 have intermeshing pinions 38, so that one of said rollers 11 being driven by the belt 37, both of said feed rollers 11 will be positively driven through the medium of pinions 38. The shaft 39 of the final beater 15 is driven through the medium of a belt 40 which runs over a pulley 41 on said shaft 39 and over a drive pulley 42 on shaft 32. On the shaft 32 also is a pinion 43 which meshes with a gear wheel 44 on the shaft 45 of roller 14. The numeral 46 indicates a pipe to conduct steam or hot air to concave 13 for maintaining the same heated to the proper degree.

I would state furthermore that while the illustrated example constitutes a practical embodiment of my invention, I do not limit myself strictly to the exact details herein

illustrated, since, manifestly, the same can be considerably varied without departure from the spirit of the invention as defined in the appended claims.

Having thus described my invention, I claim:

1. In a machine for subjecting furs to treatment, brushing means, beater means, a heated structure positioned between the brushing means and beater means, and means to guide a piece of fur past said brushing means over the said heated structure and past said beater means.
2. In a machine for subjecting fur to treatment to raise and straighten the hair, a heated structure, and means to guide the fur over the surface of said heated structure to cause the hair to be raised and straightened.
3. In a machine for treating furs, a hair

straightening means in the form of a concave, means to maintain said concave heated, and means to cause furs to move in proximity to said concave.

4. In a machine for treating furs, a hair straightening means in the form of a concave, and means to maintain said concave heated; together with a roller to bend the fur into contact with said concave.

5. In a machine for brushing, raising and straightening the hair on a skin, brushing means, a preliminary beater, hair raising means, and a final beater, said hair raising means being disposed between the two beaters, together with means to cause fur to successively pass adjacent the first beater, against the hair raising means, and then past the final beater.

SAMUEL FRIEDMAN.
